T. T. RODEBERG

STAPLE DRIVER

Filed Feb. 23, 1923

INVENTOR:

Thomas T. Rodeberg
BY A. M. Carlson
ATTORNEY.

UNITED STATES PATENT OFFICE.

THOMAS T. RODEBERG, OF MONTEVIDEO, MINNESOTA.

STAPLE DRIVER.

Application filed February 23, 1923. Serial No. 620,576.

To all whom it may concern:

Be it known that I, THOMAS T. RODEBERG, a citizen of the United States, residing at Montevideo, in the county of Chippewa and State of Minnesota, have invented certain new and useful Improvements in Staple Drivers, of which the following is a specification.

My invention relates to staple drivers, and the object is to provide an inexpensive and easily operated, efficient device of said kind.

In the accompanying drawing.—

Fig. 1 is a side elevation of the device with staples in it.

Fig. 2 is a left hand end view of Fig. 1.

Fig. 3 is a right hand end view of Fig. 2, showing how it drives a staple into wood.

Fig. 4 is a bottom view of the lower right hand corner of Fig. 1.

Fig. 5 is a side view and Fig. 6 is an end view of one of several clips holding the staples ready to be quickly placed in the driver.

Referring to the drawing by reference numerals, 7 designates the main frame which may have a wooden handle 8, and is fixed at 9 and 10 respectively to a horizontal frame bar 11 and a short horizontally flat frame portion 12 having an aperture 13 through which the staples escape one at a time when being driven.

Each staple is driven downward by a flat punch 14 formed at the lower end of a plunger 15 having a pin 16 to limit its upward movement, and a head 17 to strike on when driving a staple, and a spring 18 holding the plunger normally in raised position. The punch 14 is guided also by a clip 19 secured by two screws 20, one of which holds also a finger 21, whose function is to hold one end 22 of a long contraction coil spring 23, said end of the spring extending through a hole 24 in the frame 7. The other end of the spring is secured at 25 to the rear end of a tube 26 which normally serves as a housing and guide for the spring.

Secured to the tube 26 is a follower 27 of inverted U-shape in cross section and straddling the staple supporting bar 11. Its rear end has a finger catch 28 and its front end serves to move the staple 29 forward against the vertical portion 7^a of the

frame 7 so as to be ready to be driven by the punch 14.

The staples are held down on the bar 11 by a guiding bar 30 having one end secured at 31, the other end at 32 (see Fig. 1).

33 is a channel strip (see Figs. 5 and 6) used as a clip for holding a number of, say about 50 staples at a time, ready to be slipped upon the upper edge of bar 11. One end of each clip is provided with guards 34 to prevent the staples sliding out at that end.

The clips are filled with staples either in the process forming the staples or by some inexpensive automatic device (not shown) and when each clip is full a rubber band 35 is slipped over the clip and the staples to hold the latter in place until wanted.

In the operation of the device small staples, like those used in window shades and window screens may be driven home by a blow of the hand upon the cap 17, but for larger staples a mallet or hammer may be used upon the head 17. As soon as the plunger is released of each blow it is raised again by the spring 18, and when the bar 11 is empty or nearly empty of staples, the operator pulls the follower 27 to about the position 27^a, the spring 25 being long and limber enough for such movement of the follower. A clip 33 is then dropped in straddling position upon the bar 11, as at 33^a, and its rubber band or like means 35 cut or removed and all the staples swept from the clip and in between the staple holding bar 11 and its guard strip 30. This done the follower is replaced on bar 11 where spring 25 will constantly pull it against the new supply of staples.

What I claim is:

1. A staple driver having an open frame forming a horizontal staple holding bar, a vertical body portion extending at about right angles upward from the front end of the horizontal bar, and a curved handle connecting said two bars, a plunger slidable in the vertical body portion and having its upper end provided with a head and a spring engaging said head to raise the plunger, means limiting the raising of the plunger, the lower end of the plunger forming a punch arranged to drive one staple at a time through a slotted hole in the frame close

by the front end of the staple supporting bar, a guiding strip fixed near above the staple supporting bar to prevent raising of the staples, a channel-shaped follower 5 straddling the horizontal bar to push the staples toward the punch and a contracting coil spring arranged to pull the follower forward, said spring being long enough to permit removal of the follower from the bar without detaching either end of the spring 10 while the bar receives a supply of staples.

2. The structure specified in claim 1, and a tubular housing fixed at one side of the follower to contain, guide and protect the coil spring. 15

In testimony whereof I affix my signature.

THOMAS T. RODEBERG.
